UNITED STATES PATENT OFFICE.

CHARLES K. SHERWOOD, OF NEW YORK, N. Y.

DESIGN FOR A CHIN-REST AND TAILPIECE.

49,783.

Specification for Design.

Patented Oct. 17, 1916.

Application filed April 20, 1916. Serial No. 92,557. Term of patent 7 years.

To all whom it may concern:

Be it known that I, CHARLES K. SHERWOOD, a citizen of the United States, and a resident of the city of New York, borough of the Bronx, in the county of Bronx and State of New York, have invented a new, original, and ornamental Design for a Chin-Rest and Tailpiece, of which the following is a specification, reference being had to the accompanying drawings forming part thereof.

Figure 1 is a plan view of a chin rest and tailpiece for violins showing my new design; and Fig. 2 is an edge view of the same.

I claim:

The ornamental design for a chin rest and tailpiece as shown.

CHARLES K. SHERWOOD.
